CHAMPAGNE BUCKET

Walter S. Taylor, Hammondsport, N.Y.

Filed Jan. 7, 1965, Ser. No. 83,315

Term of patent 14 years

(Cl. D44—15)

FIG. 1 is a top plan view of a champagne bucket showing my new design;

FIG. 2 is a top plan view on an enlarged scale and with the cover omitted for convenience of illustration;

FIG. 3 is a vertical sectional view.

I claim:

The ornamental design for a champagne bucket, as shown and described.
